UNITED STATES PATENT OFFICE.

GEORGE E. OKELL, OF LOS ANGELES, CALIFORNIA, ASSIGNOR TO MAX LIVINGSTON, OF LOS ANGELES, CALIFORNIA.

CORE-DRILL.

No. 842,577.

Specification of Letters Patent.

Patented Jan. 29, 1907.

Applied for November 8, 1906. Serial No. 341,930.

To all whom it may concern:

Be it known that I, GEORGE E. OKELL, a citizen of the United States, residing at Los Angeles, in the county of Los Angeles and State of California, have invented new and useful Improvements in Core-Drills, of which the following is a specification.

My invention relates to that class of drill-heads which are used for obtaining cores out of the ground being drilled or examined; and the object thereof is to provide a drill of simple construction and which can be operated at a minimum cost and which is adapted for use in drilling through hard substances.

Heretofore drills have been used in which diamonds have been used in the cutting edges thereof, thereby making the drill costly, and sometimes when in operation the drill would come to a crevice and the diamond, being loosed through continuous use, would drop out and be lost, and its place must be refilled with another diamond, thereby making the operation exceedingly costly. I am also aware that drills have been constructed in which vertical slots were constructed in the lower or drilling end, and the edges of the slots were chamfered and flared, and that with such drills chilled shot were used; but in drills of such construction the shot or other abrading substance used for drilling is liable to become wedged between the core and the body of the drill, thereby expanding the bottom of the drill and causing it to cut a larger hole than is necessary, or if it did not expand such drill-head to break the core, and thereby cause trouble. In my improved tubular core-drill I avoid these objections by giving the slot in the lower end of the tubular body an inclination to the vertical axis of the drill-head and by making the opposing faces of the slot parallel.

In the drawings, Figure 1 is a fragmentary side elevation, partly in central section, of my improved drill-head. Fig. 2 is a section 45 on line 2 2 of Fig. 1. Fig. 3 is a perspective view of the lower portion of the drill-head.

4 is the tubular body of the drill-head which is interiorly threaded at its upper end to removably secure it to the driving-head 5,

which is externally threaded on the lower end 50 thereof for the reception of the body. The driving-head has a central channel 6 therein, the upper end of which is interiorly threaded for the reception of a hollow driving-rod 7. In the lower end of the tubular body is a diagonal slot 8, which I have found by repeated experiments produces the best results when at an angle of forty-five degrees to the vertical axis of the body and the body rotated so that the top of the slot is in advance of the bottom, as shown in Fig. 1, the arrow indicating the direction in which the head is to rotate. The advantage of having a slot set at an inclination with the top in advance is that the abrading material 10, which may be 65 chilled cast-iron shot or other abrading substance, is forced downwardly underneath the bottom of the drill-head by the rotation thereof, where they effectively bite into the substance being drilled. The advantage of 70 having the sides of the slot parallel is that when the abrading material enters the slot it is forced downwardly on an inclined plane toward the bottom of the drill and underneath the same and is not forced inwardly or 75 outwardly to cause wedging either between the core or between the drill-head and the outside material. The upper surface of the driving-head is inwardly beveled, as shown in Fig. 1, so as to provide a cup to cause any 80 considerable-sized substance that may fall down the hole to rest against the driving-rod rather than against the outside of the hole. The tubular body is of any desired length, and as the bottom is worn off the slot is further cut upwardly until the whole body is worn out, when a new body can be replaced upon the driving-head and the tool is as good as new. The slot in the lower part of the head is long enough and large enough to permit the water which is forced down the hollow driving-rod to flow freely out of the upper portion to carry the material cut by the abrading substance upwardly.

What I claim is—

1. A tubular drill having a diagonal slot in the lower end thereof.
2. A tubular drill having a slot in its lower

end substantially at an angle of forty-five degrees to its vertical axis.

3. A tubular drill having a slot in its lower end substantially at an angle of forty-five degrees to its vertical axis and having a driving-head secured to the other end, said driving-head having a cup in its upper surface.

In witness that I claim the foregoing I have hereunto subscribed my name this 29th day of October, 1906.

GEORGE E. OKELL.
